ROTARY GUN

Louis D. Peik, Mishawaka, Ind., assignor to The
American Foundry Equipment Company, New
York, N. Y., a corporation of Delaware

Application March 14, 1931, Serial No. 522,541

7 Claims. (Cl. 51—8)

The invention relates in general to equipment for cleaning materials, and more particularly to a rotary gun for delivering a blast of sand or other abrasive.

5 According to one form which the invention may take, a drum-shaped distributing reservoir is provided which is rotated about a main axis by suitable means. A plurality of flexible hose connections may be connected to the distributing reservoir having individual nozzles at the end thereof for delivering a mixture of air and abrasive at high velocity therefrom. A man inlet pipe may be provided on the axis of rotation for delivering to said distributing reservoir a mixture of 10 pre-carburetted abrasive particles and air. Suitable means may be provided for spreading and contracting the individual nozzles so as to vary the effective blasting area. Suitable means may be provided for protecting the distributing reservoir from the blasting action of the abrasive 15 which it distributes to the several nozzles.

It is within the contemplation of the present invention to rotate the gun at not higher than a certain peripheral speed below which the greatest efficiencies are developed. The rotary gun, according to the invention, may be used to clean the surface of a plate or other material on one side only, or a pair of guns may be placed on opposite sides of the material to be cleaned 20 and blasts directed simultaneously to clean opposite sides. With the gun constructed and operated as hereinafter described more in detail, it has been found that no separate booster jets of air are required.

25 The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming 45 a part thereof, in which

Fig. 1 is a central longitudinal section taken through a rotary gun according to the invention;

Fig. 2 is a section on the line 2—2 of Fig. 1;

50 Fig. 3 is an end view of the rotary gun; and Fig. 4 indicates more or less diagrammatically two guns of the character described cleaning simultaneously the opposite surfaces of a sheet of steel or the like.

55 In the following description and in the claims, various details will be identified by specific names for convenience, but they are intended to be as generic in their application as the art will permit.

Like reference characters denote like parts in 60 the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, the rotary nozzle or gun is journaled in a bearing housing, indicated by 11, to which is connected a gear housing, indicated by 10. Annular seats, indicated by 12 and 13, are provided in which are positioned conical roller bearing assemblies 14 and 15 for withstanding both radial and axial stress.

Located within the assemblies 14 and 15 is a hollow spindle 16 having a flange 17 at one end and also a circular boss 18. The flange 17 is provided with a cylindrical sleeve member 19 for forming a tight seal with the bearing housing 11 as hereinafter described more in detail.

Secured to the other end of the hollow spindle 16 is a worm wheel 20 keyed to spindle 16 by key 21. A nut 22 is threaded upon the end of spindle 16 to lock the gear 20 in position on the spindle 16.

The worm wheel 20 is made with a deep annular recess in which is positioned a conical shield 23 which is suitably connected to the seat 12 to guard the oil in the bottom of the gear housing 10 from being lost in the bearing housing 11.

Meshing with the worm wheel 20 is a worm 24 which is partially immersed in oil (not shown) in the bottom of the gear housing 10. The worm 24 is mounted upon a suitable shaft 74 which in turn is mounted in conical roller bearing assemblies 72 and 73, which in turn are mounted in seats in caps 70 and 71 which are suitably bolted to the gearing housing 10, as indicated particularly in Fig. 2.

The gearing housing 10 is provided with a removable cover 26 bolted thereto by bolts 28, the cover having a boss 27 to which is secured by screws 30 a conduit 29 which may be made of flexible material such as rubber and which passes through the boss 27 and the rotary spindle 16, as indicated.

It will be understood that the various joints in the gearing housing and bearing housing are sealed by suitable packing, indicated by 31, 32, 33, etc.

The housing reservoir 40 is centered upon the boss 18 and secured to flange 17 by a plurality of bolts 41. The housing 40 is cylindrical and has a header 42 secured to one end thereof with a suitable gasket 53 therebetween.

The header 42 is provided with a plurality of bosses or nipples 43 in which are positioned flexible hose conduits of rubber or other suitable material, indicated by 45. Conduits 45 are secured to nipples 43 by wood screws 46 and have nozzle 120

bodies 47 secured at their outer ends. Individual nozzles 48 are secured to the nozzle bodies 47, as indicated.

If desired, a metal cone member 70 may be spot-welded to header 42 as indicated at 71. This assists in preventing uneven firing of the nozzles and prevents the distributing reservoir from getting out of balance due to uneven distribution of the abrasive in the reservoir.

10 The header 42 opposite the supply conduit 29 is provided with a recess 44, to the wall of which is secured a stud 49 on which is slidably mounted a collar 50. Links 52 pivotally connect the collar 50 to the respective nozzle bodies 47. A setscrew 15 51 passes through the collar 50 to clamp the collar at any desired position on the stud 49 to position radially the nozzles 48 in the desired radius, as indicated by the dotted lines in Fig. 1.

It will be understood that a mixture of pre-carburetted air and sand is supplied to the feed conduit 29 from a source not shown. It has been found, in blasting with a rotary gun that the efficiency drops off very rapidly when the gun is rotated at a peripheral speed of the individual 20 nozzles 48 above speeds of the order of 700 feet per minute and below speeds of the order of 100 feet per minute as the efficiency, as measured by the metal removed from the test sheet in ounces per minute, falls off very materially at speeds not 25 within this range.

30 The operation of the distributing reservoir 40 and the rotation of the gun assists in distributing the carburetted sand equally between the several nozzles. It is important that the sand be distributed equally to the several nozzles so that each nozzle does substantially the same amount of work in order to obtain maximum efficiency of the gun.

35 The mixture of sand and air issuing from the feed conduit 29 strikes the header 42 with maximum force at the recess or pocket 44. This fills up with sand and acts as a cushion to prevent premature wearing through of the metal. The sand is distributed evenly to the flexible conduits 45 45 due to the rotation of the gun, as above described, feeding the carburetted abrasive equally to the nozzles 48. It will be understood that a suitable source of power will be applied to the shaft 76 which will drive the shaft 74 through the 50 coupling 75 (Fig. 2).

55 The advantage of the rotating nozzles is freedom from streaks on the work as the work travels past the gun which would otherwise occur if the nozzles were not rotating. Each individual nozzle following immediately after the preceding nozzle and delivering its stream of abrasive causes a more uniform distribution of the abrasive on the entire length and breadth of the work as it is moved through the blasting apparatus.

60 These rotary guns are useful especially in cleaning large castings and work of large area such as sheet material. In addition to the cleaning action of a single gun cleaning one surface alone, material to be cleaned may be passed between two rotary guns, as indicated in Fig. 4, both sides of the material being cleaned simultaneously. Due to the efficient cleaning action of these guns and the comparatively large area of work which can be cleaned, the material passing 65 70 between two rotary guns can be cleaned with great efficiency in a comparatively small time. In other words, the material, in this case the sheet 60 in Fig. 4, may be passed comparatively

rapidly between the oppositely disposed rotary guns, indicated by 61 and 62.

While certain novel features of the invention have been disclosed and are pointed out in the annexed claims, it will be understood that various omissions, substitutions and changes may be made by those skilled in the art without departing from the spirit of the invention.

What is claimed is:

1. In a rotary gun, a bearing, a hollow spindle in said bearing, a driven power-transmitting member on said spindle, a distributing reservoir secured to said spindle, flexible conduits secured to said reservoir, nozzles secured to said conduits, and means for controlling the spread of said 80 nozzles. 85

2. In a rotary gun, a housing, a bearing in said housing, a hollow spindle in said bearing, a driven power-transmitting member on said spindle and in said housing, a distributing reservoir secured to said spindle, flexible conduits secured to said reservoir, nozzles secured to said 95 conduits, and means for controlling the spread of said nozzles.

3. In a rotary abrasive blast gun, a bearing 100 housing comprising spaced bearing seats, bearing assemblies in said seats, a hollow spindle in said assemblies having a supporting flange at one end, a drum shape distributing reservoir secured to said flange, a plurality of individual nozzles 105 secured to said distributing reservoir, a worm wheel secured to the other end of said spindle, a worm engaging said worm wheel, a gear housing secured to said bearing housing surrounding said worm and worm wheel, a cover closing 110 said gear housing and having a hollow boss, a single stationary feed pipe secured within said boss and passing through said spindle to feed said distributing reservoir with a pre-carburetted mixture of abrasive particles and carrying fluid. 115

4. In a rotary abrasive blast gun, a stationary bearing, a rotary distributing reservoir journaled in said bearing, a conduit feeding said reservoir axially of said bearing, flexible hoses secured to said reservoir, nozzles on the ends of said hoses, 120 a stud secured to said reservoir, a collar on said stud and links pivoted to said collar and to said nozzles.

5. In a rotary abrasive blast gun, a rotary distributing reservoir, means for feeding a pre-carburetted mixture of abrasive particles and carrying fluid to said reservoir, a plurality of flexible conduits connected to said reservoir, nozzles on the ends of said conduits, means for controlling the spread of said nozzles, and means for 125 continuously revolving said nozzle about a common axis of revolution.

6. In a rotary abrasive blast gun, a stationary bearing, a rotary distributing reservoir journaled in said bearing, a conduit feeding said reservoir 130 axially of said bearing, a header closing said reservoir and having a plurality of nipples, flexible hoses in said nipples, nozzles on the ends of said hoses, said header carrying a recess in line with said conduit, a stud secured to the wall of 140 said recess, a collar on said stud and links pivoted to said collar and to said nozzles.

7. In a rotary gun, a plurality of individual nozzles, means for feeding said nozzles with abrasive particles and carrying fluid, means for revolving 145 said nozzles about a common axis of revolution and means for adjusting the spread of said nozzles with respect to said common axis of revolution.

LOUIS D. PEIK.
